[57] ABSTRACT

A coilable partition of the type which is stored within a coil box and movable in translation across a wall opening incorporates a passdoor at the leading end thereof in which the intermediate door stile and the lintel section above the door are coilable.

COILABLE PARTITION WITH PASSDOOR

BACKGROUND OF THE INVENTION

In Carlo U.S. Pat. No. 3,090,424 issued May 21, 1963, and assigned to the same assignee as this invention there is disclosed a passdoor arrangement at the lead end of a coil partition. This passdoor is carried in an opening formed between a pair of vertical stiles or jambs and is movable, as a unit, into the interior of the coil box when the partition was retracted. However, since no portion of the passdoor section was, itself, coilable the retraction of the passdoor within the coil box resulted in the creation of an unfavorable pull angle between the passdoor section and the coiling partition itself in the coiled condition of the wall. While the construction of the Carlo patent has been successful and has uniquely solved the problem of forming a passdoor in a coiling partition, nevertheless, the rigid door section provides some difficulties in installations where full automatic retraction is desired.

SUMMARY OF THE INVENTION

The present invention is directed to an improved passdoor arrangement for a coiling partition in which the first stile and the lintel section above the door are coilable apart from the door, thus providing a more compact arrangement requiring less storage area and providing a good pull angle for complete automatic retraction and extension. This is accomplished by providing a coilable lintel section above the door and by hinging the door to the lead post stile. Thus, when the partition is retracted into the coil box, the coilable lintel section can follow the curvature of the coil while the passdoor itself is extended linearly into the coil box.

The passdoor itself is provided with guide means in the form of a vertically movable blade or shoe which, in the lowered position, engages the floor track and serves as a latch. The shoe further provides for linear guided movement of the door within the coil box concurrently with the coiling movement of the intermediate stile and the lintel or head section.

An important object of the invention is the provision of an improved passdoor arrangement for a coiling partition in which the intermediate stile and the lintel section above the door are coilable.

Another object of the invention is the provision, in a coiling partition, of a passdoor in which the door itself is guided for linear movement within the coil box while the lintel section above the door coils onto the roll.

These and other objects and advantages of the invention will be apparent from the following description, the accompanying drawings and the appended claims.

BRIEF DESCRIPTION OF THE DRAWINGS

FIG. 1 is an elevational view of a coiling partition incorporating a passdoor constructed according to this invention;

FIG. 2 is a fragmentary transverse section taken generally along the line 2-2 of FIG. 1;

FIG. 3 is an enlarged broke-away section through the lintel section of the door taken generally along the line 3-3 of FIG. 1;

FIG. 4 is an enlarged fragmentary section through the passdoor taken generally along the line 4-4 of FIG. 1;

FIG. 5 is a diagrammatic plan view showing a typical coil box and track arrangement for this invention;

FIG. 6 is an enlarged vertical section through the sub-track within the coil box taken generally along the line 6-6 of FIG. 5; and

FIG. 7 is a view similar to FIG. 6 but showing the manner in which the passdoor is received within the coil box.

10 DESCRIPTION OF PREFERRED EMBODIMENT

Referring first to FIG. 1, there is illustrated a coilable partition 10 consisting of a longitudinal series of vertically arranged and interconnected coilable slats 12 extending between a fixed head section or slotted track (not shown) positioned generally at a ceiling line 13 and a floor slot or track (not shown in FIG. 1) positioned generally flush with a floor reference line 14. The partition 10 and the interconnected arrangement of the individual slats may be constructed according to the teachings of Carlo U.S. Pat. Nos. 3,090,424, 3,090,425 and 3,090,426. Such partitions commonly are provided with a flexible guide and support tape or band 15 at the top thereof riveted or suitably connected to the individual slats 12 and provided with a longitudinal series of trolley rollers (not shown) received within the track at the head section. The partition is further provided with a continuous bottom band tape 18 which is received within a suitable slot formed within the floor track. The assembly of slats is retained by a series of internal cables 20, and the extended movement thereof is affected by an upper cable 22 received in the head track section and a lower cable 23 received in the lower track section. The cables 22 and 23 are wound upon a suitable drive and take-up drum carried within the coil box.

The present invention is directed to improvements in an integrated passdoor section illustrated generally at 30 in FIG. 1 at the leading end of the partition 10. The 40 passdoor section of this invention includes an intermediate coilable vertical stile 32 (FIGS. 1, 3 and 4). The vertical stile 32 may consist of the same material as that of the slats 12, and for the purpose of illustration, it is shown as being made of wood. The vertical stile 32 thus is connected to the end of the partition 12, and is also attached, in the manner of the slats 12, to the upper tape 15 and the lower tape 18.

The passdoor section further includes a second vertical stile which comprises a lead stile 34. The lead stile 34 is spaced longitudinally from the intermediate stile 32 and similarly extends between the head section and the floor slot and, with the integrated passdoor of this invention, if fact defines the lead post for the coiling partition. For this purpose, the lead stile 34 may have formed, on its exposed end, a vertical nose or bumper 35 of vinyl covered elastomeric material.

The upper portions of the stiles 32 and 34 are joined by a coilable door lintel section 36 comprising a series of vertical coilable slats 36a which are formed similarly to the slats 12. The slats 36a extend longitudinally between the stiles 32 and 34 and are joined under longitudinal compression by two of the cables 20. The coilable slats 36a extend only partially vertically with respect to the stiles and define, with the stiles, a passdoor opening 37. The lower ends of the intermediate slats 36a are tied to the stiles by a flexible internal connector shown at 38.

An essentially rigid and non-coilable passdoor 40 is received beneath the lintel section 36 and between the stiles 32 and 34 in the opening 37, and is hinged to the lead stile 34. The passdoor 40, for the sake of appearance, may be formed with an outer covering 42 (FIG. 4) which is vertically grooved to match the exterior appearance of the slats 12 and 36. The door 40 is preferably mounted on double swinging hinges 42 so that it may be swung through the opening in either direction. Single pivot hinges may also be used, in which case it is necessary to consider the direction of coiling within the coil box, as will be described below.

The door 40 includes floor guide means consisting of a vertically movable blade or guide 45 laterally adjacent the intermediate stile 32 (FIG. 1). The guide 45 is movable vertically between a raised position in which it is above the line 14 and clear of the floor track and a lowered position as shown in full line in FIG. 1 in which the end of the guide 45 extends slightly below the lower edge of the tape 18. The door may be provided with a manual operator 46 by means of which the guide 45 may be raised or lowered. When lowered, the guide 45 is engaged with the floor slot and thus provides a latch for the door. It further provides means for guiding the door itself linearly within the coil box while the partition and the lintel section is being coiled.

The lower ends of the stiles 32 and 34 are connected by a flexible strap 50 which, in effect, forms a linear continuation of the tape 18. The strap 50 is formed with an essentially rigid laterally offset section illustrated at 52 in FIG. 2. The lateral offset section 52 is positioned adjacent the guide 45 and assures that the guide is always lowered on the same side of the strap 50.

Often, in installations of coiling partitions, it is desirable to install the floor and head section tracks along a curved path so that the partition is caused to negotiate curves and bends within the room. This may be both a decorative and a functional requirement, and is frequently one of the advantages of specifying a coiling partition. The guide means 45 assures that the door 40 tracks with the partition and the coiling lintel section 36 as the partition progresses around such curves. However, since the door 40 is essentially rigid it tends to bridge the curves, or form a cord line across the curves, while the lintel section and the attached stiles follow the curvature. In this condition, i.e., while negotiating a curve, the lateral spacing between the vertical stiles 32 is somewhat diminished. Provision is accordingly made to accommodate such linear dimensional changes by providing a resilient or soft vertical jamb 55 (FIG. 4) for the free edge of the door 40. As shown in FIG. 4, the jamb 55 consists of a core 56 of resilient material and a vinyl covering 58. The jamb 55 is thus constructed to accommodate, by compression and deformation, changes in the lateral spacing between the stiles 32 and 34 which occurs when negotiating a curve.

A typical coil box is illustrated at 60 in FIGS. 5 and 6. The box contains the vertical shaft or spool 62 onto which the partition is wound as a series of convolutions. The partition is not shown in FIG. 5 in the interests of clarity. A typical floor track is shown at 65 which terminates just inwardly of the entrance of the coil box at 66 adjacent a guide roller 67. Means for guiding the passdoor 40 for linear movement concurrent with the

coiling movement of the header or lintel sections consists of a subtrack illustrated generally at 70 and shown in section in FIG. 6. The sub-track 70 is positioned vertically below the level of the principle track 65 and is provided with guiding flanges 72 which engage only the blade or guide 45. Thus, when the partition is coiled into the coil box as illustrated at FIG. 7, the passdoor 40 is guided linearly into the box by the sub-track 70.

In the coiled condition, as shown, the intermediate stile 32 and the lintel section 36 consisting of the slats 36a are shown as being partially wrapped on the coil. A negligible pull angle is formed between the slats 36a and the lead stile 34 so that the automatic retraction system can retract the partition and the associated passdoor fully into the coil box 60. Similarly, when it is desired to extend the partition, the automatic extension system provides an extension pull on the cables 22 and 23, which will extract the passdoor section by an unwinding of the coiled slats and by a reverse linear movement of the passdoor 40 into the principle floor track section 65.

The offset section 52 is related to the guide 45 in such a manner that the offset is always on the side of the partition facing the coil within the coil box 60, to assure that the guide 45 can carry the door 40 linearly on the subtrack section 70. The relative movement of the door 40 with respect to the lintel section 36 is illustrated by the arrow 75 in FIG. 2. Accordingly, if it is desired to have the door open one way only, it is necessary that the door also open in direction of the arrow 75.

It is accordingly seen that this invention provides a passdoor in which the lintel section and the intermediate stile are coilable, thus retaining an acceptably low pull angle between it and the lead post 34. The arrangement is accordingly one which requires a minimum of storage space within the coil box and which permits fully automatic operation between the extended and the retracted conditions.

While the form of apparatus herein described constitutes a preferred embodiment of the invention, it is to be understood that the invention is not limited to this precise form of apparatus, and that changes may be made therein without departing from the scope of the invention.

What is claimed is:

1. In a coilable partition including a longitudinal series of vertical coilable slats guided for transverse movement into and out of a coil box along a fixed head section at the top and a floor slot at the bottom thereof, the improvement in a integrated passdoor at the leading end of such partition comprising an intermediate vertical stile connected to the leading edge of said partition and extending between said head section and said floor slot, a lead vertical stile spaced longitudinally from said intermediate stile and defining a lead post for said partition, a series of vertical coilable slats extending longitudinally between said stiles along said head section and extending only partially vertically forming a door lintel, and an essentially rigid and non-coilable passdoor received beneath said lintel between said stiles and hinged to said lead stile providing for coiling movement of said intermediate stile and lintel in said coil box accompanied by linear movement of said door within said box.

2. The coiling wall of claim 1 further comprising floor guide means in said door mounted for vertical movement into and out of engagement with said floor slot, and operator means in said door for selectively raising and lowering said guide means.

3. In a coilable partition adapted to move between curved ceiling and floor tracks and storable in a coil box at one end of said tracks, the improvement in pass-door construction comprising an intermediate stile joined to one end of said partition and extending vertically between said tracks, a lead stile spaced laterally from said intermediate stile and also extending vertically between said tracks, a coilable header section extending laterally between said stiles and defining therewith a door opening, a non-coiling door in said

opening, means hinging said door to said lead stile, and guide means on said door extending laterally adjacent said intermediate stile and engageable with one of said tracks.

5 4. The partition of claim 3 further comprising resilient means vertically interposed between said door and said intermediate stile to accommodate movement of said partition and header section and door around curves in said tracks.

10 5. The partition of claim 3 further comprising a guide in said coil box engageable only with said door guide means to provide for linear movement of said door concurrently with coiling movement of said header section.
